(57) **ABSTRACT**

An integrated process for production of gasoline has been described. The process includes a C_5 - C_6 isomerization zone with an associated deisohexanizer, two C_7 isomerization zones separated by a deisoheptanizer, and a reforming zone. The use of two C_7 isomerization zones eliminates the need for the large recycle stream from the deisoheptanizer. The C_6 cycloalkanes and heavies from the deisohexanizer are fed to the second C_7 isomerization zone to increase the amount of 95 RONC gasoline produced. A higher percentage of 95 RONC gasoline may be achieved by further recycling C_6 from deisoheptanizer overhead back to C_5 - C_6 isomerization zone. Higher gasoline yields and higher percentage of 95 RONC gasoline is achieved over the whole naphtha complex with operating costs savings by fully integrating the C_5 - C_6 isomerization zone, two C_7 isomerization zones, deisohexanizer and deisoheptanizer columns.

FIG. 4

INTEGRATED PROCESS FOR PRODUCTION OF GASOLINE

BACKGROUND

Gasoline specifications are becoming stricter and more difficult for refiners to meet. For example, it is difficult for hydrocracker based refineries to meet the aromatics specifications in the Euro-V gasoline standard while maximizing 95 RONC (research octane number clear) without having a heavy naphtha export stream. For example, certain standards may limit gasoline to concentrations of no more than 35 lv % aromatics; concentration of no more than 1.0 lv % benzene; distillation specifications and Reid vapor pressure (RVP) limit etc. The heavy naphtha stream has lower value, thus reducing the refiner's profitability.

A typical hydrocracker based refinery naphtha block includes a C₅-C₆ isomerization zone and a catalytic reforming zone. In order to minimize aromatics production, C₇ needs to be removed from the feed to the catalytic reforming zone. This can be done with a second naphtha splitter or a side draw from a naphtha splitter, for example. Although this approach minimizes the amount of aromatics produced from C₅, it does not allow for 95 RONC gasoline production due to the low blending octanes of components in the C₇ stream when blending directly to gasoline pool.

A solution is to use a single stage C₇ isomerization zone with a large recycle stream to maximize the octane of the isomerate. In order to maximize the octane, a deisoheptanizer (DIHP) column is used to produce an overhead stream, a side cut stream, and a bottom stream. The overhead stream primarily comprises high octane multi-branched C₇ hydrocarbons. The side draw stream is a mixture of single-branched, normal, and cycloalkane C₇s. This is a lower octane stream and is recycled back to reactor to be converted to multi-branched C₇s. The bottom stream comprises n-heptane, C₇ cycloalkanes and heavies. In order to achieve a high proportion of 95 RONC gasoline, this C₇ isomerization zone configuration results in very high operating costs due to large recycle stream and a lack of on-stream flexibility due to the single isomerization stage.

Therefore, there is a need for a more flexible process of making gasoline with an increased amount of 95 RONC.

BRIEF DESCRIPTION OF THE DRAWINGS

FIG. 1 is an illustration of a gasoline process.

FIG. 2 is an illustration of an improved gasoline process.

FIG. 3 is an illustration of one embodiment of a process of the present invention.

FIG. 4 is an illustration of another embodiment of a process of the present invention.

SUMMARY AND DETAILED DESCRIPTION

An integrated process for production of gasoline with 95 RONC has been developed. The process includes a C₅-C₆ isomerization zone, two C₇ isomerization zones, and a reforming zone. The use of two C₇ isomerization zones eliminates the need for the large recycle stream from the deisoheptanizer. This configuration results in significant savings in operating costs and increases the total gasoline yield from the complex.

The first C₇ isomerization zone is designed to isomerize C₇ paraffins. The product from the first C₇ isomerization zone is sent to a deisoheptanizer column in order to separate a C₇ iso-paraffin-containing stream (typically 20-100 mol %

iso-paraffins, or 30-100 mol %) as an overhead stream and a C₇ cycloalkane-containing stream (typically 20-100 mol % cycloalkane, or 30-100 mol %, or 40-100 mol %, or 50-100 mol %) as a bottom stream. The C₇ cycloalkane-containing stream is sent to the second C₇ isomerization zone. The second C₇ isomerization zone is designed to maximize the isomerization of C₇ cycloalkanes to higher octane cycloalkanes. Including a second C₇ isomerization zone enables better molecular management and improves the overall operation of the process.

The feed and operating conditions in the two C₇ isomerization zones are different in order to increase the octane and selectivity for the process. The first C₇ isomerization zone is optimized to increase the isomerization of C₇ paraffins and C₅⁺ retention. This is accomplished by running at lower temperature, which favors the formation of multi-branch C₇ paraffins, which have higher blending octanes. The choice of low temperature also reduces the cracking and therefore increases the C₅⁺ retention. Because the first C₇ isomerization zone has the maximum feed, operating at mild conditions has a significant impact on preserving total C₅⁺ yield.

The presence of C₇ cycloalkane compounds in the feed to the first C₇ isomerization zone also inhibits and reduces paraffin cracking, increasing the C₅⁺ yield. The lower temperatures in the first C₇ isomerization zone also favor the formation of methylcyclohexane, resulting in easier separation between multi-branched C₇ paraffins and C₇ cycloalkanes in the downstream deisoheptanizer. Methylcyclohexane has a boiling point of 100.4° C. (213.7° F.), which is much higher compared to other C₇ multi-branched paraffins and C₇ cyclopentanes. Specifically, the dimethylcyclopentanes have boiling points between 87.8-91.7° C. (190.1-197° F.), and multi-branched C₇ paraffins have boiling points between 79.2-89.8° C. (174.6° F. to 193.6° F.). The dimethylcyclopentanes include 1,1-dimethylcyclopentane, trans-1,3-dimethylcyclopentane and trans-1,2-dimethylcyclopentane.

The aromatics level in the first C₇ isomerization zone should be kept as low as possible to prevent significant exotherms due to aromatics saturation. For C₇ streams containing high levels of benzene (e.g., greater than about 2.5 wt %), it is desirable to saturate some or all of the aromatic compounds before isomerizing the C₇ stream in the first C₇ isomerization zone. A C₇ stream with a high benzene level would be sent first to a hydrogenation zone with a hydrogenation catalyst where the benzene is converted to cyclohexane with very low yield losses. The resulting C₇ stream with cyclohexane would then be fed to the first C₇ isomerization zone. Some of the cyclohexane formed from benzene will be isomerized to higher octane methylcyclopentane in the first C₇ isomerization zone.

The feed to the second C₇ isomerization zone is primarily C₇ cycloalkanes, typically 20-100 mol % cycloalkanes, or 30-100 mol %, or 40-100 mol %, or 50-100 mol %.

Cycloalkanes contain hydrogen and carbon atoms arranged in a structure containing a single ring with the ring having all single C—C bonds. There may be hydrocarbon side chains on the ring. Cyclopentanes are cycloalkanes (also known as naphthenes) that contain 5-member carbon rings and any number and type of side chains, for example, methylcyclopentane, 1,2-dimethylcyclopentene, ethylcyclopentane, etc. Cyclohexanes are cycloalkanes (also known as naphthenes) that contain 6-member carbon rings and any number and type of side chains, for example, cyclohexane, methylcyclohexane, ethylcyclohexane, etc.

The second C₇ isomerization zone is operated under conditions favoring the formation of cyclopentanes over

cyclohexanes. The second C_7 isomerization zone is optimized to maximize the isomerization of C_7 cycloalkanes by operating at higher temperature. The cycloalkanes are more resistant to cracking than paraffins, so the higher operating temperatures in the second C_7 isomerization zone are possible without significant loss to light ends. Furthermore, at higher temperatures, equilibrium favors formation of dimethylcyclopentanes, which have a research octane numbers about 10 higher than methylcyclohexane.

The higher temperature of the second isomerization reaction zone helps meet the final blended gasoline specifications. This can be particularly important when meeting the Euro-V gasoline specification for RONC and E100 (vol % evaporated at 100° C.). For naphtha feed lean in C_5 and C_6 , it is challenging to have enough light components to meet the E100 distillation specification (e.g. ≥ 46 vol %) for Euro-V gasoline. By converting methylcyclohexane to dimethylcyclopentanes, the percent evaporated at 100° C. will be increased. These isomerization reactions increase the RONC of the stream and reduces the boiling points of the components in the product.

The higher temperatures in the second C_7 isomerization zone shift the cycloalkane equilibrium to convert a portion of the cyclohexanes into cyclopentanes; these isomerization reactions are endothermic. When the cycloalkane concentration to the second C_7 isomerization zone is greater than about 65 mol %, a temperature drop along the catalyst beds in the second C_7 isomerization zone is observed, thus limiting the conversion of cyclohexanes to cyclopentanes. If the temperature drop in the second C_7 isomerization zone can be moderated, then an increased equilibrium level of higher octane cyclopentanes can be attained. The addition of an aromatic-containing stream to the second C_7 isomerization zone helps to achieve this result. The aromatic-containing stream comprises at least one aromatic compound, such as, but not limited to, benzene and/or toluene. It contains the aromatic compounds in the range of 0.1-100 wt %, or 0.1-90 wt %, or 0.1-80 wt %, or 0.1-70 wt %, or 0.1-60 wt %, or 0.1-50 wt %, or 1-100 wt %, or 1-90 wt %, or 1-80 wt %, or 1-70 wt %, or 1-60 wt %, or 1-50 wt %, or 5-100 wt %, or 5-90 wt %, or 5-80 wt %, or 5-70 wt %, or 5-60 wt %, or 5-50 wt %, or 10-100 wt %, or 10-90 wt %, or 10-80 wt %, or 10-70 wt %, or 10-60 wt %, or 10-50 wt %, or 15-100 wt %, or 15-90 wt %, or 15-80 wt %, or 15-70 wt %, or 15-60 wt %, or 15-50 wt %, or 20-100 wt %, or 20-90 wt %, or 20-80 wt %, or 20-70 wt %, or 20-60 wt %, or 20-50 wt %. Heat is produced when the aromatics are saturated at the conditions of the second C_7 isomerization zone. The heat generated moderates the temperature drop or results in a net temperature increase in the second C_7 isomerization zone. Since a higher reactor exit temperature has been attained, this leads to an enhanced equilibrium conversion of the cyclohexanes to higher octane cyclopentanes.

Additional benefits of adding an aromatic-containing stream to the second C_7 isomerization zone include: the heat produced from aromatics saturation can reduce the energy needed to heat the feed of the second C_7 isomerization zone; the aromatic levels in the naphtha complex are reduced which help meet the gasoline pool specifications such as Euro-V specifications; and the aromatics convert to saturated cyclohexanes with a portion isomerizing to the higher octane cyclopentanes. For example, benzene would be saturated to form cyclohexane (83.0 RONC) and some would then isomerize to form methylcyclopentane (91.3 RONC). The aromatic-containing stream can be obtained from a reformate splitter or an additional fractionation on the naphtha splitter, for example, or from any other suitable sources.

The improved process enables much lower operating and capital costs, lower initial catalyst loading, and increased yields. For example, in some embodiments, the improved process configuration lowers the operating costs by about 57%, reduces the capital costs by about 11%, increases the octane barrels by about 4%, and increases operating flexibility compared with the existing process. The increased operating flexibility results from the fact that each C_7 isomerization zone can be independently controlled to maximize the different isomerization reactions and yield.

One aspect of the invention is an integrated process for production of gasoline. In one embodiment, the process comprises separating a naphtha feed in a naphtha splitter into a light stream comprising C_6 and lighter boiling hydrocarbons, a C_7 stream comprising C_7 hydrocarbons, and a heavy stream comprising C_8 and heavier hydrocarbons. At least a portion of the light stream from the naphtha splitter is isomerized in a C_5 - C_6 isomerization zone at isomerization conditions to form a C_5 - C_6 isomerization effluent. At least a portion of the C_5 - C_6 isomerization effluent is deisohexanized in a deisohexanizer into at least a first stream comprising multi-branched C_6 paraffins and a bottom stream comprising C_6 cycloalkanes and heavies. The C_7 stream from the naphtha splitter is isomerized in a first C_7 isomerization zone at first isomerization conditions favoring the formation of multi-branched C_7 paraffins, and cyclohexanes to form a first C_7 isomerization effluent. At least a portion of the first C_7 isomerization effluent is deisoheptanized in a deisoheptanizer into at least a first stream comprising multi-branched C_7 paraffins, and a bottom stream comprising n- C_7 paraffins and C_7 cycloalkanes. The bottom stream from the deisoheptanizer is combined with the bottom stream from the deisohexanizer to form a combined stream. The combined stream is isomerized in a second C_7 isomerization zone at isomerization conditions favoring the formation of cyclopentanes over cyclohexanes to form a second C_7 isomerization effluent. The heavy stream from the naphtha splitter is reformed in a reforming zone under reforming conditions forming a reformate effluent. One or more of: at least a portion of the C_5 - C_6 isomerization effluent, the first stream from the deisoheptanizer, the second C_7 isomerization effluent, or the reformate effluent are blended to form a gasoline blend.

In some embodiments, deisoheptanizing at least the portion of the first C_7 isomerization effluent in the deisoheptanizer into at least the first stream comprising multi-branched C_7 paraffins and the bottom stream comprising n- C_7 paraffins and C_7 cycloalkanes comprises deisoheptanizing at least the portion of the first C_7 isomerization effluent in the deisoheptanizer into at least an overhead stream comprising C_6 paraffins, the first stream comprising multi-branched C_7 paraffins, and the bottom stream comprising n- C_7 paraffins and C_7 cycloalkanes; and further comprising: recycling the overhead stream from the deisoheptanizer to the C_5 - C_6 isomerization zone.

In some embodiments, deisohexanizing the C_5 - C_6 isomerization effluent in the deisohexanizer into at least the first stream comprising multi-branched C_6 paraffins and the bottom stream comprising C_6 cycloalkanes and heavies comprises deisohexanizing the C_5 - C_6 isomerization effluent in the deisohexanizer into at least the first stream comprising multi-branched C_6 paraffins, and the bottom stream comprising C_6 cycloalkanes and heavies, and a lower sidecut stream comprising n- C_6 paraffins and single-branched C_6 paraffins; and further comprising: recycling the lower sidecut stream from the deisohexanizer to the C_5 - C_6 isomerization zone.

In some embodiments, the process further comprises introducing an aromatic-containing stream comprising at least one aromatic to the second C₇ isomerization zone.

In some embodiments, the first C₇ isomerization zone conditions include a temperature in a range of 40° C. to 235° C. (104° to 455° F.), or the second C₇ isomerization zone conditions include a temperature in a range of 175° C. to 325° C. (347 to 617° F.), or both.

In some embodiments, the process further comprises blending at least one additional stream with the gasoline blend.

In some embodiments, the process further comprises hydroprocessing the naphtha feed before separating the naphtha feed.

In some embodiments, the C₇ stream from the naphtha splitter further comprises at least one aromatic compound, and the process further comprises hydrogenating at least a portion of the aromatic compounds in the C₇ stream from the naphtha splitter before isomerizing the C₇ stream from the naphtha splitter.

In some embodiments, the process further comprises separating the first C₇ isomerization effluent into an overhead stream comprising hydrogen and C₄ and lower boiling hydrocarbons and a second heavy stream comprising C₅ and heavier hydrocarbons before deisoheptanizing at least the portion of the first C₇ isomerization effluent, and wherein deisoheptanizing at least the portion of the first C₇ isomerization effluent comprises deisoheptanizing the second heavy stream.

In some embodiments, the process further comprises the process further comprises separating the second C₇ isomerization effluent into a second overhead stream comprising hydrogen and C₄ and lower boiling hydrocarbons and a C₇ isomerized stream comprising C₅ and heavier hydrocarbons and wherein blending one or more of: the first stream from the deisohexanizer, the first stream from the deisoheptanizer, the second C₇ isomerization effluent, or the reformate effluent to form the gasoline blend comprises blending one or more of: the first stream from the deisohexanizer, the first stream from the deisoheptanizer, the C₇ isomerized stream, or the reformate effluent to form the gasoline blend.

In some embodiments, the process further comprises separating the C₅-C₆ isomerization effluent into at least a third overhead stream comprising C₄ and lower boiling hydrocarbons and a C₅-C₆ isomerized stream comprising C₅ and heavier hydrocarbons, and wherein deisohexanizing at least the portion of the C₅-C₆ isomerization effluent comprises deisohexanizing the C₅-C₆ isomerized stream.

In some embodiments, the process further comprises at least one of: sensing at least one parameter of the process and generating a signal or data from the sensing; generating and transmitting a signal; or generating and transmitting data.

Another aspect of the invention is an integrated process for production of gasoline. In one embodiment, the process comprises separating a naphtha feed in a naphtha splitter into a light stream comprising C₆ and lighter boiling hydrocarbons, a C₇ stream comprising C₇ hydrocarbons, and a heavy stream comprising C₈ and heavier hydrocarbons. At least a portion of the light stream from the naphtha splitter is isomerized in a C₅-C₆ isomerization zone at isomerization conditions to form a C₅-C₆ isomerization effluent. At least a portion of the C₅-C₆ isomerization effluent is deisohexanized in a deisohexanizer into at least a first stream comprising multi-branched C₆ paraffins and a bottom stream comprising C₆ cycloalkanes and heavies. The C₇ stream from the naphtha splitter is isomerized in a first C₇ isomer-

ization zone at first isomerization conditions favoring the formation of multi-branched C₇ paraffins and cyclohexanes to form a first C₇ isomerization effluent. At least a portion of the first C₇ isomerization effluent is deisoheptanized in a deisoheptanizer into at least an overhead stream comprising C₆ paraffins, a sidecut stream comprising multi-branched C₇ paraffins, and a bottom stream comprising n-C₇ paraffins and C₇ cycloalkanes. The overhead stream from the deisoheptanizer is recycled to the C₅-C₆ isomerization zone. The bottom stream from the deisoheptanizer is combined with the bottom stream from the deisohexanizer to form a combined stream. The combined stream is isomerized in a second C₇ isomerization zone at second isomerization conditions favoring the formation of cyclopentanes over cyclohexanes to form a second C₇ isomerization effluent. The heavy stream from the naphtha splitter is reformed in a reforming zone under reforming conditions forming a reformate effluent. One or more of: the first stream from the deisohexanizer, the sidecut stream from the deisoheptanizer, the second C₇ isomerization effluent, or the reformate effluent are blended to form the gasoline blend.

In some embodiments, deisohexanizing the C₅-C₆ isomerization effluent in the deisohexanizer into at least the first stream comprising multi-branched C₆ paraffins and the bottom stream comprising C₆ cycloalkanes and heavies comprises deisohexanizing the C₅-C₆ isomerization effluent in the deisohexanizer into at least the first stream comprising multi-branched C₆ paraffins, and the bottom stream comprising C₆ cycloalkanes and heavies, and a lower sidecut stream comprising n-C₆ paraffins and single-branched C₆, and further comprising recycling the lower sidecut stream from the deisohexanizer to the C₅-C₆ isomerization zone.

In some embodiments, the process further comprises introducing an aromatic-containing stream comprising at least one aromatic to the second C₇ isomerization zone.

In some embodiments, the first isomerization conditions include a temperature in a range of 40° C. to 235° C. (104° to 455° F.), or the second isomerization conditions include a temperature in a range of 175° C. to 325° C. (347 to 617° F.), or both.

In some embodiments, the process further comprises blending at least one additional stream with the gasoline blend.

In some embodiments, the process further comprises hydroprocessing the naphtha feed before separating the naphtha feed.

In some embodiments, the C₇ stream from the naphtha splitter further comprises at least one aromatic compound, and the process further comprises: hydrogenating at least a portion of the aromatic compounds in the C₇ stream from the naphtha splitter before isomerizing the C₇ stream from the naphtha splitter.

In some embodiments, the process further comprises separating the first C₇ isomerization effluent into an overhead stream comprising hydrogen and C₄ and lower boiling hydrocarbons and a second heavy stream comprising C₅ and heavier hydrocarbons before deisoheptanizing at least the portion of the first C₇ isomerization effluent, and wherein deisoheptanizing at least the portion of the first C₇ isomerization effluent comprises deisoheptanizing the second heavy stream; or separating the second C₇ isomerization effluent into a second overhead stream comprising hydrogen and C₄ and lower boiling hydrocarbons and a C₇ isomerized stream comprising C₅ and heavier hydrocarbons and wherein blending one or more of: the first stream from the deisohexanizer, the first stream from the deisoheptanizer, the second C₇ isomerization effluent, or the reformate effluent to

form the gasoline blend comprises blending one or more of: the first stream from the deisohexanizer, the first stream from the deisoheptanizer, the C₇ isomerized stream, or the reformate effluent to form the gasoline blend; or separating the C₅-C₆ isomerization effluent into at least a third overhead stream comprising C₄ and lower boiling hydrocarbons and a C₅-C₆ isomerized stream comprising C₅ and heavier hydrocarbons, and wherein deisohexanizing at least the portion of the C₅-C₆ isomerization effluent comprises deisohexanizing the C₅-C₆ isomerized stream.

FIG. 1 illustrates one example of a hydrocracker-based naphtha complex. The naphtha feed stream 105 is sent to a naphtha hydrotreater 110. The hydrotreated feed stream 115 is sent to a naphtha splitter 120 where it is separated into a light stream 125, a C₇ stream 130, and a heavy stream 135. The light stream 125 comprises C₆ and lighter boiling hydrocarbons, the C₇ stream 130 comprises C₇ hydrocarbons, and the heavy stream 135 comprises C₈ and heavier hydrocarbons.

The light stream 125 from the naphtha splitter 120 is sent to a C₅-C₆ isomerization zone 140 where the C₆ and lighter boiling hydrocarbons are isomerized to branched hydrocarbons forming the C₅-C₆ isomerization effluent 145.

The heavy stream 135 from the naphtha splitter 120 is reformed in reformer 150 to form reformate 155.

The C₇ stream 130 is sent to a C₇ isomerization zone 160 to form a C₇ isomerization effluent 165. The C₇ isomerization effluent 165 is sent to a deisoheptanizer 170 where it is separated into an overhead stream 175, a bottom stream 180, and a recycle stream 185. The overhead stream 175 comprises multi-branched C₇ hydrocarbons, and the bottom stream 180 comprises C₇ cycloalkanes and heavies.

The recycle stream 185 comprises n-heptane, single-branched C₇ paraffins and C₇ cycloalkanes and is recycled back to the C₇ isomerization zone 160.

The C₅-C₆ isomerization effluent 145, the overhead stream 175 from the deisoheptanizer 170, the bottom stream 180 from the deisoheptanizer 170, and the reformate 155 are combined to form a gasoline stream 190. Optionally, a C₄ stream 195 comprising n-C₄ and iso-C₄ paraffins can be included in the gasoline stream 190.

However, this arrangement involves increased capital and operating costs when producing high percentage of 95 RONC gasolines. To achieve the higher octanes, the recycle stream 185 is typically greater than or equal to the feed rate of the C₇ stream 130. As a result, the vessel size and amount of catalyst in the C₇ isomerization zone 160 and the size of deisoheptanizer 170 become much large in order to process the combined feed consisting of C₇ stream 130 and the recycle stream 185. The arrangement also results in much higher utility costs for the deisoheptanizer 170.

FIG. 2 illustrates one embodiment of an integrated complex containing two C₇ isomerization zones.

The naphtha feedstocks to the naphtha complex that can be used herein include hydrocarbons ranging from C₄ to C₁₂ consisting of normal paraffins, iso-paraffins, cycloalkanes and aromatics. The naphtha feedstock may also contain low concentrations of unsaturated hydrocarbons, sulfur-containing hydrocarbons, nitrogen-containing hydrocarbons, metals and other impurities.

The naphtha feed stream 205 is sent to a naphtha hydrotreater 210. Hydrotreating is a process in which hydrogen gas is contacted with a hydrocarbon stream in the presence of suitable catalysts which are primarily active for the removal of oxygenates and heteroatoms, such as sulfur, nitrogen, and metals from the hydrocarbon feedstock. In hydrotreating, hydrocarbons with double and triple bonds

may be saturated. Aromatics may also be saturated. Typical hydrotreating reaction conditions include a temperature of about 290° C. (550° F.) to about 455° C. (850° F.), a pressure of about 3.4 MPa (500 psig) to about 6.2 MPa (900 psig), a liquid hourly space velocity of about 0.5 hr⁻¹ to about 4 hr⁻¹, and a hydrogen rate of about 168 to about 1,011 Nm³/m³ oil (1,000-6,000 scf/bbl). Typical hydrotreating catalysts include at least one Group 8 metal, preferably iron, cobalt and nickel, and at least one Group 6 metal, preferably 10 molybdenum and tungsten, on a high surface area support material, preferably alumina. Other typical hydrotreating catalysts include zeolitic catalysts, as well as noble metal catalysts where the noble metal is selected from palladium and platinum.

The hydrotreated feed stream 215 is sent to a naphtha splitter 220 where it is separated into a light stream 225, a C₇ stream 230, and a heavy stream 235. The light stream 225 comprises C₆ and lighter boiling hydrocarbons, the C₇ stream 230 comprises C₇ hydrocarbons, and the heavy stream 235 comprises C₈ and heavier hydrocarbons. The naphtha splitter 220 could comprise a divided wall column or two columns in series, for example.

The light stream 225 from the naphtha splitter 220 is sent to a C₅-C₆ isomerization zone 240. The C₅-C₆ isomerization zone 240 can be any type of isomerization zone that takes a stream of C₅-C₆ straight-chain hydrocarbons or a mixture of straight-chain, branched-chain, and cycloalkanes and converts straight-chain hydrocarbons in the feed mixture to branched-chain hydrocarbons and branched hydrocarbons to 20 more highly branched hydrocarbons, thereby producing an effluent having branched-chain and straight-chain hydrocarbons. The C₅-C₆ isomerization zone 240 can include one or more isomerization reactors, feed-effluent heat exchangers, inter-reactor heat exchangers, driers, sulfur guards, separator, stabilizer, compressors, deisopentanizer column, deisohexanizer column, and other equipment as known in the art (not shown). A hydrogen-rich gas stream (not shown) is typically mixed with the light stream 225 and heated to reaction temperatures. The hydrogen-rich gas stream, for example, comprises about 50-100 mol % hydrogen. The hydrogen can be separated from the reactor effluent, compressed and recycled back to mix with the light stream 225.

The light stream 225 and hydrogen are contacted in the C₅-C₆ isomerization zone 240 with an isomerization catalyst 45 forming C₅-C₆ isomerization effluent 245. The catalyst compositions that can be used in the C₅-C₆ isomerization zone 240 include traditional isomerization catalysts including chlorided platinum alumina, crystalline aluminosilicates or zeolites, and other solid strong acid catalysts such as tungstated zirconia, sulfated zirconia and modified sulfated zirconia. Suitable catalyst compositions of this type will exhibit 50 selective and substantial isomerization activity under the operating conditions of the process.

Another suitable isomerization catalyst is a solid strong acid catalyst that comprises a sulfated support of an oxide or hydroxide of a Group IVB (IUPAC 4) metal, preferably zirconium oxide or hydroxide, at least a first component that is a lanthanide element or yttrium component, and at least a second component being a platinum-group metal component. The catalyst optionally contains an inorganic-oxide binder, especially alumina.

The support material of the solid strong acid catalyst 60 comprises an oxide or hydroxide of a Group IVB (IUPAC 4). In one embodiment the Group IVB element is zirconium or titanium. Sulfate is composited on the support material. A component of a lanthanide-series element is incorporated into the composite by any suitable means. The lanthanide

series element component may be selected from the group consisting of lanthanum, cerium, praseodymium, neodymium, promethium, samarium, europium, gadolinium, terbium, dysprosium, holmium, erbium, thulium, ytterbium and lutetium. Suitable amounts of the lanthanide series element component are in the range of about 0.01 to about 10 wt % on an elemental basis, of the catalyst. A platinum-group metal component is added to the catalytic composite by any means known in the art to effect the catalyst, e.g., by impregnation. The platinum-group metal component may be selected from the group consisting of platinum, palladium, ruthenium, rhodium, iridium, or osmium. Amounts in the range of from about 0.01 to about 2 wt % platinum-group metal component, on an elemental basis are suitable.

Optionally, the catalyst is bound with a refractory inorganic oxide. The binder, when employed, usually comprises from about 0.1 to 50 wt %, preferably from about 5 to 20 wt %, of the finished catalyst. The support, sulfate, metal components and optional binder may be composited in any order effective to prepare a catalyst useful for the isomerization of hydrocarbons. Examples of suitable atomic ratios of lanthanide or yttrium to platinum-group metal for this catalyst are at least about 1:1; for example about 2:1 or greater; such as about 5:1 or greater. The catalyst may optionally further include a third component of iron, cobalt, nickel, rhenium or mixtures thereof. For example, iron may be present in amounts ranging from about 0.1 to about 5 wt % on an elemental basis. In an exemplary embodiment, the solid strong acid isomerization catalyst is sulfated zirconia or a modified sulfated zirconia.

Another class of suitable isomerization catalysts for use herein includes the chlorided platinum alumina catalysts. The aluminum is preferably an anhydrous gamma-alumina with a high degree of purity. The catalyst may also contain other platinum group metals. The term "platinum group metals" refers to noble metals excluding silver and gold that are selected from the group consisting of platinum, palladium, germanium, ruthenium, rhodium, osmium, and iridium. These metals demonstrate differences in activity and selectivity such that platinum has now been found to be the most suitable for this process. The catalyst will contain from about 0.1 to about 0.25 wt % of the platinum. Other platinum group metals may be present in a concentration of from about 0.1 to about 0.25 wt %. The platinum component may exist within the final catalytic composite as an oxide or halide or as an elemental metal. The presence of the platinum component in its reduced state has been found most suitable for this process. The chloride component termed in the art "a combined chloride" is present in an amount from about 2 to about 10 wt % based upon the dry support material. The use of chloride in amounts greater than about 5 wt % has been found to be the most beneficial for this process. The inorganic oxide preferably comprises alumina and more preferably gamma-alumina, eta-alumina, and mixtures thereof.

It is generally known that high chlorided platinum-alumina catalysts of this type are highly sensitive to sulfur and oxygen-containing compounds. Therefore, the use of such catalysts requires that the feedstock be relatively free of such compounds. A sulfur concentration no greater than about 0.5 ppm is generally required for use of high chloride platinum-alumina catalysts. The presence of sulfur in the feedstock serves to temporarily deactivate the catalyst by platinum poisoning. Activity of the catalyst may be restored by hot hydrogen stripping of sulfur from the catalyst composite or by lowering the sulfur concentration in the incoming feed to below about 0.5 ppm so that the hydrocarbon will desorb the

sulfur that has been adsorbed on the catalyst. Water can act to permanently deactivate the catalyst by removing high activity chloride from the catalyst and replacing it with inactive aluminum hydroxide. Therefore, water, as well as oxygenates, in particular C₁-C₅ oxygenates, that can decompose to form water, can only be tolerated in very low concentrations. In general, this requires a limitation of oxygenates in the feed to about 0.1 ppm or less. The feedstock may be treated by any method that will remove water and sulfur compounds. Sulfur may be removed from the feedstock stream by hydrotreating. A variety of commercial dryers are available to remove water from the feed components. Adsorption processes for the removal of sulfur and water from hydrocarbon streams are also well known to those skilled in the art.

Operating conditions within the isomerization zone are selected to maximize the production of isoalkane product from the feed components. Temperatures within the isomerization zone will usually range from about 40° C. to about 235° C. (104° F. to 455° F.). Lower reaction temperatures usually favor equilibrium mixtures of isoalkanes versus normal alkanes. Lower temperatures are particularly useful in processing feeds composed of C₅ and C₆ alkanes where the lower temperatures favor equilibrium mixtures having the highest concentration of the most branched isoalkanes. When the feed mixture is primarily C₅ and C₆ alkanes, temperatures in the range of from about 60° C. to about 160° C. are suitable. The isomerization zone may be maintained over a wide range of pressures. Pressure conditions in the isomerization of C₄-C₆ paraffins range from about 700 kPa(a) to about 7000 kPa(a). In other embodiments, pressures for this process are in the range of from about 2000 kPa(g) to 5000 kPa(g). The feed rate to the reaction zone can also vary over a wide range. These conditions include liquid hourly space velocities ranging from about 0.5 to about 12 hr⁻¹ however, with some embodiments having space velocities between about 1 and about 6 hr⁻¹.

The heavy stream 235 from the naphtha splitter 220 is sent to reformer 250 to form reformat 255. In a common form, the reforming process can employ catalyst particles in several reaction zones interconnected in a series flow arrangement. Typically, a heavy naphtha stream and a hydrogen gas stream are preheated and charged to a reforming zone containing typically two to five reactors in series. Suitable heating means are provided between reactors to compensate for the net endothermic heat of reaction in each of the reactors. Reactants may contact the catalyst in individual reactors in either upflow, downflow, or radial flow fashion, with the radial flow mode being preferred. The catalyst may be contained in a fixed-bed system or, preferably, in a moving-bed system with associated continuous catalyst regeneration. Alternative approaches to reactivation of deactivated catalyst include semiregenerative operation, which includes shutting down the entire unit for catalyst regeneration and reactivation, or swing-reactor operation, which includes isolating a single reactor from the system, regenerating and reactivating while the other reactors remain on stream. Typically, continuous catalyst regeneration in conjunction with a moving-bed system is disclosed, inter alia, in, e.g., U.S. Pat. No. 3,647,680; 3,652,231; 3,692,496; and 4,832,921.

Generally, effluent from the reforming zone is passed through a cooling means to a separation zone, often maintained at about 0-65° C., where a hydrogen gas stream is separated from a liquid stream commonly called "unstabilized reformat". The resultant hydrogen stream can then be recycled through suitable compressing means back to the

reforming zone. Usually, the liquid phase from the separation zone is withdrawn and processed in a fractionating system in order to adjust the butane concentration, thereby controlling front-end volatility of the resulting reformate.

The reforming reactors can contain any suitable catalyst. The catalyst particles are typically comprised of one or more Group VIII (IUPAC 8-10) noble metals (e.g., platinum, iridium, rhodium, and palladium) and a halogen combined with a porous carrier, such as a refractory inorganic oxide. U.S. Pat. No. 2,479,110, for example, teaches an alumina-platinum-halogen reforming catalyst. Although the catalyst may contain about 0.05 to about 2.0 wt % of Group VIII metal, a less expensive catalyst, such as a catalyst containing about 0.05 to about 0.5 wt % of Group VIII metal may be used. In addition, the catalyst may contain indium and/or a lanthanide series metal such as cerium. The catalyst particles may also contain one or more Group IVA (IUPAC 14) metals (e.g., tin, germanium, and lead), such as described in U.S. Pat. Nos. 4,929,333, 5,128,300, and the references cited therein. The halogen is typically chlorine, and alumina is commonly the carrier. Suitable alumina materials include, but are not limited to, gamma, eta, and theta alumina. One property related to the performance of the catalyst is the surface area of the carrier. Preferably, the carrier has a surface area of about 100 to about 500 m²/g. The activity of catalysts having a surface area of less than about 130 m²/g tend to be more detrimentally affected by catalyst coke than catalysts having a higher surface area. Generally, the particles are usually spheroidal and have a diameter of about 1.6 to about 3.1 mm (about 1/16 to about 1/8 inch), although they may be as large as about 6.35 mm (about 1/4 inch) or as small as about 1.06 mm (about 1/24 inch). In a particular reforming reaction zone, however, it is desirable to use catalyst particles which fall in a relatively narrow size range.

Typical feed inlet temperature for the reformers are between 440 and 580° C. (824 and 1076° F.), or between 500 and 580° C. (932 and 1076° F.), or between 540 and 580° C. (1004 and 1076° F.), or at least above 540° C. (932° F.). The reformer reactors may have different operating temperatures, for example, with a first reforming reactor having a temperature between 500 to 540° C. (932 to 1004° F.) and a second, subsequent reforming reactor having a temperature greater than 540° C. (1004° F.). The reformers can be operated at a range of pressures generally from atmospheric pressure of about 0 to about 6,895 kPa(g) (about 0 psig to about 1,000 psig), or about 276 to about 1,379 kPa(g) (about 40 to about 200 psig). The reaction conditions also include a liquid hour space velocity (LHSV) in the range from 0.6 hr⁻¹ to 10 hr⁻¹. Preferably, the LHSV is between 0.6 hr⁻¹ and 5 hr⁻¹, with a more preferred value between 1 hr⁻¹ and 5 hr⁻¹, and with a most preferred value between 2 hr⁻¹ and 5 hr⁻¹. The shorter residence time is especially preferred when utilizing the higher temperatures. The catalyst also has a residence time in the reformers of between 0.5 hours and 36 hours.

The C₇ stream 230 is sent to a first C₇ isomerization zone 260 to form a first C₇ isomerization effluent 265. The first C₇ isomerization zone 260 is operated under conditions favoring the formation of multi-branched C₇ paraffins and cyclohexanes.

The catalyst composites that can be used in the first C₇ isomerization zone 260 include traditional isomerization catalysts including chlorided platinum alumina, crystalline aluminosilicates or zeolites, and other solid strong acid catalysts such as tungstated zirconia, sulfated zirconia and modified sulfated zirconia. Suitable catalyst compositions of

this type will exhibit selective and substantial isomerization activity under the operating conditions of the process.

Operating conditions within the first C₇ isomerization zone 260 are selected to favor the formation of multi-branched C₇ paraffins and cyclohexane rings. Temperatures within the first C₇ isomerization zone 260 will usually range from about 40° C. to about 235° C. (104° F. to 455° F.), with reactor inlet temperatures ranging from about 80° C. to 130° C., or from about 90° C. to 120° C. The lower reaction temperatures will favor higher equilibrium mixtures of multi-branched C₇ paraffins, will reduce the hydrocracking of C₇ paraffins to undesired C₅⁻ light ends, and favor the formation of cyclohexanes. In some embodiments, it is advantageous to keep the temperature rise in the C₇ isomerization zone 260 within these ranges to prevent excessive hydrocracking of C₇ paraffins which leads to light ends and loss of C₅⁺ gasoline yields. The benzene and toluene levels should be kept as low as possible in C₇ stream 230 to prevent significant exotherms within C₇ isomerization zone 260. For high aromatic-containing feeds (e.g., greater than about 2.5 wt %), the C₇ stream 230 can be mixed with a hydrogen-rich gas stream (as described above) and processed in an aromatic hydrogenation unit that utilizes a suitable aromatic hydrogenation catalyst that results in aromatic saturation with little or no hydrocracking activity so as to prevent yield losses to C₅⁻ light ends. By removing the aromatic saturation from the first C₇ isomerization zone 260, the large exotherm due to high aromatics is removed, thus allowing first C₇ isomerization zone 260 to operate at the desired lower temperatures. The effluent from the aromatic hydrogenation unit is then fed to the first C₇ isomerization zone 260.

The first C₇ isomerization zone 260 may be maintained over a wide range of pressures. Pressure conditions range from about 700 kPa(a) to about 7000 kPa(a). In other embodiments, pressures range from about 1800 kPa(a) to 3200 kPa(a). The feed rate to the first C₇ isomerization zone can also vary over a wide range. These conditions include liquid hourly space velocities ranging from about 0.5 to about 12 hr⁻¹, with some embodiments having liquid hourly space velocities between about 1 and about 6 hr⁻¹.

The first C₇ isomerization effluent 265 is sent to a deisohexanizer 270 where it is separated into an overhead stream 275, and a bottom stream 280. The overhead stream 275 comprises multi-branched C₇ hydrocarbons, and the bottom stream 280 comprises n-C₇ and C₇ cycloalkanes.

The bottom stream 280 is sent to the second C₇ isomerization zone 285. The second C₇ isomerization zone 285 is operated under conditions favoring the formation of cyclopentanes over cyclohexanes.

The catalyst composites that can be used in the second C₇ isomerization zone 285 include traditional isomerization catalysts including chlorided platinum alumina, crystalline aluminosilicates or zeolites, and other solid strong acid catalysts such as tungstated zirconia, sulfated zirconia and modified sulfated zirconia. Suitable catalyst compositions of this type will exhibit selective and substantial isomerization activity under the operating conditions of the process.

Operating conditions within the second C₇ isomerization zone 285 are selected to favor the formation of cyclopentanes over cyclohexanes. Temperatures within the second C₇ isomerization zone 285 will usually range from about 175° to about 325° C. (347° to 617° F.), with reactor outlet temperatures typically above about 200° C.

The C₇ isomerization zone 285 may be maintained over a wide range of pressures. Pressure conditions range from about 700 kPa(a) to about 7000 kPa(a). In other embodi-

ments, pressures range from about 1800 kPa(a) to 3200 kPa(a). The feed rate to the C₇ isomerization zone 285 can also vary over a wide range. These conditions include liquid hourly space velocities ranging from about 0.5 to about 12 hr⁻¹, with some embodiments having liquid hourly space velocities between about 1 and about 6 hr⁻¹.

An aromatic-containing stream 290 can also be introduced into the second C₇ isomerization zone 285, if desired. The aromatic-containing stream comprises at least one aromatic compound, typically in the range of 0.1 wt-100 wt %, or 0.1-90 wt %, or 0.1-80 wt %, or 0.1-70 wt %, or 0.1-60 wt %, or 0.1-50 wt %, or 1-100 wt %, or 1-90 wt %, or 1-80 wt %, or 1-70 wt %, or 1-60 wt %, or 1-50 wt %, or 5-100 wt %, or 5-90 wt %, or 5-80 wt %, or 5-70 wt %, or 5-60 wt %, or 5-50 wt %, or 10-100 wt %, or 10-90 wt %, or 10-80 wt %, or 10-70 wt %, or 10-60 wt %, or 10-50 wt %, or 15-100 wt %, or 15-90 wt %, or 15-80 wt %, or 15-70 wt %, or 15-60 wt %, or 15-50 wt %, or 20-100 wt %, or 20-90 wt %, or 20-80 wt %, or 20-70 wt %, or 20-60 wt %, or 20-50 wt %. For embodiments with more than one isomerization reactor, the aromatic-containing stream can be preferentially fed to any one or more of the reactors. As discussed above, the saturation of the aromatics in C₇ isomerization zone 285 can provide at least a portion of the heat that moderates the temperature drop or results in a net temperature increase in the isomerization reactors such as to produce a higher exit reactor temperature. This results in a higher equilibrium conversion to the higher octane cyclopentanes. The aromatic-containing stream 290 can be any aromatic-containing stream, including, but not limited to, light reformate from reformate splitter (not shown) in reformer 250, a benzene-containing stream fractionated from the naphtha splitter 220, a toluene-containing stream fractionated from the naphtha splitter 220, or other sources.

A cycloalkane-containing stream 295 can also be introduced into the second C₇ isomerization zone 285, if desired. The cycloalkane-containing stream comprises at least one cycloalkane, typically in the range of 0.1-100 wt %, or 0.1-90 wt %, or 0.1-80 wt %, or 0.1-70 wt %, or 0.1-60 wt %, or 0.1-50 wt %, or 1-100 wt %, or 1-90 wt %, or 1-80 wt %, or 1-70 wt %, or 1-60 wt %, or 1-50 wt %, or 5-100 wt %, or 5-90 wt %, or 5-80 wt %, or 5-70 wt %, or 5-60 wt %, or 5-50 wt %, or 10-100 wt %, or 10-90 wt %, or 10-80 wt %, or 10-70 wt %, or 10-60 wt %, or 10-50 wt %, or 15-100 wt %, or 15-90 wt %, or 15-80 wt %, or 15-70 wt %, or 15-60 wt %, or 15-50 wt %, or 20-100 wt %, or 20-90 wt %, or 20-80 wt %, or 20-70 wt %, or 20-60 wt %, or 20-50 wt %. The cycloalkane-containing stream can have a cyclopentanes/cycloalkanes molar ratio of about 1:2 or less. Streams with higher molar ratios already contain high levels of cyclopentanes, and thus they are typically blended directly with the gasoline stream. The cycloalkane-containing stream 295 can be any suitable cycloalkane-containing stream, including, but not limited to, a bottom cut from a deisohexanizer column, a cycloalkane-containing straight run naphtha stream.

The first and second C₇ isomerization zones 260, 285 can include one or more isomerization reactors, feed-effluent heat exchangers, inter-reactor heat exchangers, driers, sulfur guards, separator, stabilizer, compressors and other equipment as known in the art (not shown). A hydrogen-rich gas stream (not shown) (as described above) is typically mixed with the stream 230 and with stream 280 and heated to reaction temperatures. The hydrogen can be separated from the reactor effluents, compressed and recycled back to mix with streams 230 and/or 280.

The catalysts used in the first and second C₇ isomerization zones 260, 285 can be those described above with respect to the C₅-C₆ isomerization zone 240.

The C₅-C₆ isomerization zone effluent 245, the overhead stream 275 from the deisoheptanizer 270, the second C₇ isomerization effluent 300, and the reformate 255 are combined to form a gasoline stream 305. Optionally, one or more additional streams 310 could also be included in the gasoline stream 305. For example, the additional stream 310 could be a C₄ stream comprising n-C₄ and iso-C₄ paraffins.

One or more of the naphtha hydrotreater 210, the naphtha splitter 220, the C₅-C₆ isomerization zone 240, the reforming zone 250, the first C₇ isomerization zone 260, the deisohexanizer 270, and the second C₇ isomerization zone 285 can be connected to controller 315 which can be used to monitor and control the various processes.

Any of the above lines, conduits, units, devices, vessels, surrounding environments, zones or similar may be equipped with one or more monitoring components including sensors, measurement devices, data capture devices or data transmission devices. Signals, process or status measurements, and data from monitoring components may be used to monitor conditions in, around, and on process equipment. Signals, measurements, and/or data generated or recorded by monitoring components may be collected, processed, and/or transmitted through one or more networks or connections that may be private or public, general or specific, direct or indirect, wired or wireless, encrypted or not encrypted, and/or combination(s) thereof; the specification is not intended to be limiting in this respect.

Signals, measurements, and/or data generated or recorded by monitoring components may be transmitted to one or more computing devices or systems. Computing devices or systems may include at least one processor and memory storing computer-readable instructions that, when executed by the at least one processor, cause the one or more computing devices to perform a process that may include one or more steps. For example, the one or more computing devices may be configured to receive, from one or more monitoring component, data related to at least one piece of equipment associated with the process. The one or more computing devices or systems may be configured to analyze the data. Based on analyzing the data, the one or more computing devices or systems may be configured to determine one or more recommended adjustments to one or more parameters of one or more processes described herein. The one or more computing devices or systems may be configured to transmit encrypted or unencrypted data that includes the one or more recommended adjustments to the one or more parameters of the one or more processes described herein.

FIG. 3 illustrates one embodiment of an integrated complex of the present invention.

The feedstocks, equipment, and operating conditions are the same as those discussed above with respect to FIG. 2.

The naphtha feed stream 405 is sent to a naphtha hydrotreater 410. The hydrotreated feed stream 415 is sent to a naphtha splitter 420 where it is separated into a light stream 425, a C₇ stream 430, and a heavy stream 435. The light stream 425 comprises C₆ and lighter boiling hydrocarbons, the C₇ stream 430 comprises C₇ hydrocarbons, and the heavy stream 435 comprises C₈ and heavier hydrocarbons.

The light stream 425 from the naphtha splitter 420 and hydrogen are contacted with an isomerization catalyst in a C₅-C₆ isomerization zone 440 forming C₅-C₆ isomerization effluent 445.

15

The C_5 - C_6 isomerization effluent 445 is sent to a deiso-hexanizer 450 where it is separated into at least a first stream 455 comprising multi-branched C_6 paraffins, a bottom stream 460 comprising C_6 cycloalkanes and heavies, and a lower sidecut stream 465 comprising n- C_6 paraffins and single-branched C_6 paraffins. The lower sidecut stream 465 can be recycled to the C_5 - C_6 isomerization zone 440. Alternatively, the first stream 455 could be an upper sidecut comprising multi-branched C_6 paraffins, and there could be an overhead stream (not shown) comprising C_5 paraffins. In this embodiment, the overhead stream could be recycled to the deisopentanizer column (not shown).

The heavy stream 435 from the naphtha splitter 420 is sent to reformer 470 to form reformate stream 475.

The C_7 stream 430 is sent to a first C_7 isomerization zone 480 to form a first C_7 isomerization effluent 485. The first C_7 isomerization zone 480 is operated under conditions favoring the formation of multi-branched C_7 paraffins and cyclohexanes, as described above.

The first C_7 isomerization effluent 485 is sent to a deiso-heptanizer 490 where it is separated into an overhead stream 495, and a bottom stream 500. The overhead stream 495 comprises multi-branched C_7 paraffins, and the bottom stream 500 comprises n- C_7 and C_7 cycloalkanes.

The bottom stream 500 from the deisoheptanizer 490 is sent to the second C_7 isomerization zone 505. The bottom stream 460 from the deisohexanizer 450 is also sent to the second C_7 isomerization zone 505. An aromatic-containing stream 510 can also be introduced into the second C_7 isomerization zone 505 to provide some of the heat that moderates the temperature drop or results in a net temperature increase in the second C_7 isomerization zone 505 such as to produce a higher exit reactor temperature, as discussed above.

The bottom stream 500, the bottom stream 460, and the optional aromatic-containing stream 510 are isomerized in the second C_7 isomerization zone 505, which is operated under conditions favoring the formation of cyclopentanes over cyclohexanes, as discussed above, forming second C_7 isomerization effluent 515.

The first stream 455 from the deisohexanizer 450, the overhead stream 495 from the deisoheptanizer 490, the second C_7 isomerization effluent 515, and the reformate 475 are combined to form a gasoline stream 520. Optionally, one or more additional streams 525 can be added to the gasoline stream 520.

One or more of the naphtha hydrotreater 410, the naphtha splitter 420, the C_5 - C_6 isomerization zone 440, the deiso-hexanizer 450, the reforming zone 470, the first C_7 isomerization zone 480, the deisoheptanizer 490, and the second C_7 isomerization zone 505 can be connected to controller (not shown) which can be used to monitor and control the various processes, as discussed above with respect to FIG. 2.

FIG. 4 illustrates one embodiment of an integrated complex of the present invention.

The feedstocks, equipment, and operating conditions are the same as those discussed above with respect to FIG. 2.

The naphtha feed stream 605 is sent to a naphtha hydrotreater 610. The hydrotreated feed stream 615 is sent to a naphtha splitter 620 where it is separated into a light stream 625, a C_7 stream 630, and a heavy stream 635. The light stream 625 comprises C_6 and lighter boiling hydrocarbons, the C_7 stream 630 comprises C_7 hydrocarbons, and the heavy stream 635 comprises C_8 and heavier hydrocarbons.

16

The light stream 625 from the naphtha splitter 620 and hydrogen are contacted with an isomerization catalyst in a C_5 - C_6 isomerization zone 640 forming C_5 - C_6 isomerization effluent 645.

5 The C_5 - C_6 isomerization effluent 645 is sent to a deiso-hexanizer 650 where it is separated into at least a first stream 655 comprising multi-branched C_6 paraffins, a bottom stream 660 comprising C_6 cycloalkanes and heavies, and a lower sidecut stream 665 comprising n- C_6 paraffins and 10 single-branched C_6 paraffins. The lower sidecut stream 665 can be recycled to the C_5 - C_6 isomerization zone 640. Alternatively, the first stream 655 could be an upper sidecut comprising multi-branched C_6 paraffins, and there could be 15 an overhead stream (not shown) comprising C_5 paraffins. In this embodiment, the overhead stream could be recycled to the deisopentanizer column (not shown). The heavy stream 635 from the naphtha splitter 620 is sent to reformer 670 to form reformate stream 675.

The C_7 stream 630 is sent to a first C_7 isomerization zone 20 680 to form a first C_7 isomerization effluent 685. The first C_7 isomerization zone 680 is operated under conditions favoring the formation of multi-branched C_7 paraffins and cyclohexanes, as described above.

The first C_7 isomerization effluent 685 is sent to a deiso-heptanizer 690 where it is separated into an overhead stream 695, a first stream 700, and a bottom stream 705. The overhead stream 695 comprises C_6 paraffins, the first stream 700 comprises multi-branched C_7 hydrocarbons, and the bottom stream 705 comprises n- C_7 and C_7 cycloalkanes.

30 The overhead stream 695 is recycled to the C_5 - C_6 isomerization zone 640.

The bottom stream 705 from the deisoheptanizer 690 is sent to the second C_7 isomerization zone 710. The bottom stream 660 from the deisohexanizer 650 is also sent to the second C_7 isomerization zone 710. An aromatic-containing stream 715 can also be introduced into the second C_7 isomerization zone 710 to provide some of the heat that moderates the temperature drop or results in a net temperature increase in the second C_7 isomerization zone 710, as 40 discussed above.

The bottom stream 705, the bottom stream 660, and the optional aromatic-containing stream 715 are isomerized in the second C_7 isomerization zone 710, which is operated under conditions favoring the formation of cyclopentanes 45 over cyclohexanes, as discussed above, forming second C_7 isomerization effluent 720.

The first stream 655 from the deisohexanizer 650, the first stream 700 from the deisoheptanizer 690, the second C_7 isomerization effluent 720, and the reformate 675 are combined to form a gasoline stream 725. Optionally, one or more additional streams 730 can be added to the gasoline stream 725.

55 One or more of the naphtha hydrotreater 610, the naphtha splitter 620, the C_5 - C_6 isomerization zone 640, the deiso-hexanizer 650, the reforming zone 670, the first C_7 isomerization zone 680, the deisoheptanizer 690, and the second C_7 isomerization zone 710 can be connected to controller (not shown) which can be used to monitor and control the various processes, as discussed above with respect to FIG. 2.

60

EXAMPLES

A case study was done for a hydrocracker based refinery using a naphtha feed stream 105 of 57,400 BPD to 65 hydrotreater 110. The naphtha feed was derived from Saharan crude blend including full range straight run naphtha and full range naphtha from a hydrocracker. The same feed was

used for all cases. Example 1 was the base case developed using the configuration shown in FIG. 1. Example 2 is the improved process configuration shown in FIG. 2. Example 3 is the improved process configuration with bottom stream 460 from the deisohexanizer 450, together with the bottom stream 500 from the deisoheptanizer 490 sent to the second C₇ isomerization zone 505 shown in FIG. 3. Example 4 is the improved process configuration shown in FIG. 4. The difference between Example 4 and Example 3 is that Example 4 recycles the overhead stream 695 from deisoheptanizer 690 back to the C₅-C₆ isomerization zone 640 which allows the octane of stream 695 to be further upgraded. Note that for all cases above, no aromatic stream was added to second C₇ isomerization zone. A deisopentanizer (not shown) is included in the C₅-C₆ isomerization zone in all examples. The overhead stream from the deisopentanizer comprises isopentane and is sent to blending. The bottom stream from deisopentanizer comprises n-pentane and C₆ components, which are sent to the C₅-C₆ isomerization reactors. All the studies were developed using detailed kinetic models and process simulations.

Table 1 shows the volumetric flow rates between Example 1 and Example 2 with the same fresh feed coming to the first C₇ isomerization zone (stream 130 in FIG. 1 and stream 230 in FIG. 2). As described above, the invention has eliminated the recycle stream 185 from deisoheptanizer 170 in FIG. 1. As a result, the volumetric feed rate to the first C₇ isomerization zone 260 (shown in FIG. 2) has been reduced by 55.9%, and the volumetric feed rate to deisoheptanizer 270 is also reduced by 57.5%.

The process of FIG. 2 shows a 3.5 lv % increase of C₇ isomerate product (stream 275 and 300) in FIG. 2, as compared to base case (stream 175 and 180) in FIG. 1. The process of FIG. 2 shows a 4.0% octane barrel increase.

The C₇ isomerization section (including first C₇ isomerization zone 260, second C₇ isomerization zone 285 and deisoheptanizer 270) in FIG. 2 shows a capital cost reduction by 11% due to the elimination of recycle stream 185, despite the addition of a second C₇ isomerization zone 285. Moreover, the flow scheme of FIG. 2 (Example 2) shows operating cost reduction of 57% as compared to the base case (Example 1).

TABLE 1

Case Study Summary of C ₇ Isomerization			
	Example 1	Example 2	% Change
Stream Information	FIG. 1	FIG. 2	
C ₇ fresh feed, BPD	12,332	12,332	
Recycle stream from deisoheptanizer, BPD	(stream 130)	(stream 230)	
Hydrocarbon feed to the first C ₇ isomerization zone, BPD	15,641	0	
Feed to deisoheptanizer, BPD	27,972	12,332	-55.9%
Feed to second C ₇ isomerization zone, BPD	(stream to zone 160)	(stream to zone 260)	
Feed to deisoheptanizer overhead, BPD	26,524	11,260	-57.5%
deisoheptanizer overhead, BPD	8,510	7,768	
deisoheptanizer bottom or second C ₇ isomerization effluent, BPD	(stream 175)	(stream 275)	
C ₇ isomerization effluent, BPD	2,373	3,492	
Total C ₇ product, BPD	10,883	11,260	+3.5%
deisoheptanizer overhead RONC	79.7	78.6	
deisoheptanizer bottom or second C ₇ isomerization effluent RONC	71.8	77.8	

TABLE 1-continued

Case Study Summary of C ₇ Isomerization			
	Example 1	Example 2	% Change
Total Octane Barrels	100% (base)	104% (relative to base)	+4%
Capital cost of C ₇ isomerization	100% (base)	89% (relative to base)	-11%
Operating cost of C ₇ isomerization	100% (base)	43% (relative to base)	-57%

A summary of case studies over the whole naphtha complex is shown in Table 2.

TABLE 2

Case Study Summary of whole naphtha complex				
	Example 1	Example 2	Example 3	Example 4
Configuration shown in Final Gasoline Products	FIG. 1	FIG. 2	FIG. 3	FIG. 4
91 RONC, BPD	11,707	8,582	7,752	0
95 RONC, BPD	39,205	42,638	43,436	51,143
Percentage of 95 RONC gasoline	77 lv %	83 lv %	85 lv %	100 lv %
Total Gasoline Produced, BPD	50,912	51,220	51,188	51,143
Naphtha Complex Capital Cost	100% (base)	98% (relative to base)	98% (relative to base)	102% (relative to base)
Naphtha Complex Utilities	92% (relative to base)	92% (relative to base)	95% (relative to base)	95% (relative to base)

Due to the octane barrel increases in the C₇ isomerization section shown in Table 1, Example 2 showed a percent of 95 RONC produced increases from 77 lv % to 83 lv % as compared to base case (Example 1). More importantly, total gasoline produced was also increased by 0.6 lv % together with 2% capital cost savings and 8% utility savings over the whole naphtha complex. With further integration, Example 3 showed the percentage of 95 RONC increases to 85 lv % with negligible capital cost and utility costs increase. With full integration shown in Example 4, 100 lv % of 95 RONC gasoline can be achieved. This attributes to further octane upgrade of overhead stream 695 from deisoheptanizer 690 by recycling back to the C₅-C₆ isomerization zone 640 shown in FIG. 4. The capital investment and utility costs increase due to a larger C₅-C₆ isomerization zone 640 and a bigger deisoheptanizer column 650. As compared to the configuration in FIG. 1, Examples 2-4 showed higher gasoline yield with a higher percentage of 95 RONC made. The higher percentage of 95 RONC gasoline can be extremely beneficial because refiners are moving toward more stringent gasoline specifications with higher RONC requirements.

By about, we mean within 10% of the stated value, or 5%, or 1%.

While at least one exemplary embodiment has been presented in the foregoing detailed description of the invention, it should be appreciated that a vast number of variations exist. It should also be appreciated that the exemplary embodiment or exemplary embodiments are only examples, and are not intended to limit the scope, applicability, or configuration of the invention in any way. Rather, the foregoing detailed description will provide those skilled in

the art with a convenient road map for implementing an exemplary embodiment of the invention, it being understood that various changes may be made in the function and arrangement of elements described in an exemplary embodiment without departing from the scope of the invention as set forth in the appended claims and their legal equivalents.

SPECIFIC EMBODIMENTS

While the following is described in conjunction with specific embodiments, it will be understood that this description is intended to illustrate and not limit the scope of the preceding description and the appended claims.

A first embodiment of the invention is an integrated process for production of gasoline comprising separating a naphtha feed in a naphtha splitter into a light stream comprising C_6 and lighter boiling hydrocarbons, a C_7 stream comprising C_7 hydrocarbons, and a heavy stream comprising C_8 and heavier hydrocarbons; isomerizing at least a portion of the light stream from the naphtha splitter in a C_5 - C_6 isomerization zone at isomerization conditions to form a C_5 - C_6 isomerization effluent; deisohexanizing at least a portion of the C_5 - C_6 isomerization effluent in a deisohexanizer into at least a first stream comprising multi-branched C_6 paraffins and a bottom stream comprising C_6 cycloalkanes and heavies; isomerizing the C_7 stream from the naphtha splitter in a first C_7 isomerization zone at first isomerization conditions favoring the formation of multi-branched C_7 paraffins and cyclohexanes to form a first C_7 isomerization effluent; deisoheptanizing at least a portion of the first C_7 isomerization effluent in a deisoheptanizer into at least a first stream comprising multi-branched C_7 paraffins, and a bottom stream comprising $n-C_7$ paraffins and C_7 cycloalkanes; combining the bottom stream from the deisoheptanizer with the bottom stream from the deisohexanizer to form a combined stream; isomerizing the combined stream in a second C_7 isomerization zone at second isomerization conditions favoring the formation of cyclopentanes over cyclohexanes to form a second C_7 isomerization effluent; reforming the heavy stream from the naphtha splitter in a reforming zone under reforming conditions forming a reformate effluent; blending one or more of: the first stream from the deisohexanizer, the first stream from the deisoheptanizer, the second C_7 isomerization effluent, or the reformate effluent to form a gasoline blend. An embodiment of the invention is one, any or all of prior embodiments in this paragraph up through the first embodiment in this paragraph wherein deisoheptanizing at least the portion of the first C_7 isomerization effluent in the deisoheptanizer into at least the first stream comprising multi-branched C_7 paraffins and the bottom stream comprising $n-C_7$ paraffins and C_7 cycloalkanes comprises deisoheptanizing at least the portion of the first C_7 isomerization effluent in the deisoheptanizer into at least an overhead stream comprising C_6 paraffins, the first stream comprising multi-branched C_7 paraffins, and the bottom stream comprising $n-C_7$ paraffins and C_7 cycloalkanes; and further comprising recycling the overhead stream from the deisoheptanizer to the C_5 - C_6 isomerization zone. An embodiment of the invention is one, any or all of prior embodiments in this paragraph up through the first embodiment in this paragraph wherein deisohexanizing the C_5 - C_6 isomerization effluent in the deisohexanizer into at least the first stream comprising multi-branched C_6 paraffins and the bottom stream comprising C_6 cycloalkanes and heavies comprises deisohexanizing the C_5 - C_6 isomerization effluent in the deisohexanizer into at least the first stream comprising multi-branched C_6 paraffins, and the bottom stream com-

prising C_6 cycloalkanes and heavies, and a lower sidecut stream comprising $n-C_6$ paraffins and single-branched C_6 paraffins and further comprising recycling the lower sidecut stream from the deisohexanizer to the C_5 - C_6 isomerization zone. An embodiment of the invention is one, any or all of prior embodiments in this paragraph up through the first embodiment in this paragraph further comprising; introducing an aromatic-containing stream comprising at least one aromatic to the second C_7 isomerization zone. An embodiment of the invention is one, any or all of prior embodiments in this paragraph up through the first embodiment in this paragraph wherein the first isomerization conditions include a temperature in a range of 40° C. to 235° C., or wherein the second isomerization conditions include a temperature in a range of 175° C. to 325° C., or both. An embodiment of the invention is one, any or all of prior embodiments in this paragraph up through the first embodiment in this paragraph further comprising blending at least one additional stream with the gasoline blend. An embodiment of the invention is one, any or all of prior embodiments in this paragraph up through the first embodiment in this paragraph further comprising hydroprocessing the naphtha feed before separating the naphtha feed. An embodiment of the invention is one, any or all of prior embodiments in this paragraph up through the first embodiment in this paragraph wherein the C_7 stream from the naphtha splitter further comprises at least one aromatic compound, and further comprising hydrodegenerating at least a portion of the aromatic compounds in the C_7 stream from the naphtha splitter before isomerizing the C_7 stream from the naphtha splitter. An embodiment of the invention is one, any or all of prior embodiments in this paragraph up through the first embodiment in this paragraph further comprising separating the first C_7 isomerization effluent into an overhead stream comprising hydrogen and C_4 and lower boiling hydrocarbons and a second heavy stream comprising C_5 and heavier hydrocarbons before deisoheptanizing at least the portion of the first C_7 isomerization effluent, and wherein deisoheptanizing at least the portion of the first C_7 isomerization effluent comprises deisoheptanizing the second heavy stream. An embodiment of the invention is one, any or all of prior embodiments in this paragraph up through the first embodiment in this paragraph further comprising separating the second C_7 isomerization effluent into a second overhead stream comprising hydrogen and C_4 and lower boiling hydrocarbons and a C_7 isomerized stream comprising C_5 and heavier hydrocarbons and wherein blending one or more of: the first stream from the deisohexanizer, the first stream from the deisoheptanizer, the second C_7 isomerization effluent, or the reformate effluent to form the gasoline blend comprises blending one or more of: the first stream from the deisohexanizer, the first stream from the deisoheptanizer, the C_7 isomerized stream, or the reformate effluent to form the gasoline blend. An embodiment of the invention is one, any or all of prior embodiments in this paragraph up through the first embodiment in this paragraph further comprising separating the C_5 - C_6 isomerization effluent into at least a third overhead stream comprising C_4 and lower boiling hydrocarbons and a C_5 - C_6 isomerized stream comprising C_5 and heavier hydrocarbons, and wherein deisohexanizing at least the portion of the C_5 - C_6 isomerization effluent comprises deisohexanizing the C_5 - C_6 isomerized stream. An embodiment of the invention is one, any or all of prior embodiments in this paragraph up through the first embodiment in this paragraph, further comprising at least one of sensing at least one parameter of the process and generating a signal or data

from the sensing; generating and transmitting a signal; or generating and transmitting data.

A second embodiment of the invention is an integrated process for production of gasoline comprising separating a naphtha feed in a naphtha splitter into a light stream comprising C_6 and lighter boiling hydrocarbons, a C_7 stream comprising C_7 hydrocarbons, and a heavy stream comprising C_8 and heavier hydrocarbons; isomerizing at least a portion of the light stream from the naphtha splitter in a C_5 - C_6 isomerization zone at isomerization conditions to form a C_5 - C_6 isomerization effluent; deisohexanizing at least a portion of the C_5 - C_6 isomerization effluent in a deisohexanizer into at least a first stream comprising multi-branched C_6 paraffins and a bottom stream comprising C_6 cycloalkanes and heavies; isomerizing the C_7 stream from the naphtha splitter in a first C_7 isomerization zone at first isomerization conditions favoring the formation of multi-branched C_7 paraffins and cyclohexanes to form a first C_7 isomerization effluent; deisoheptanizing at least a portion of the first C_7 isomerization effluent in a deisoheptanizer into at least an overhead stream comprising C_6 paraffins, a sidecut stream comprising multi-branched C_7 paraffins, and a bottom stream comprising n- C_7 paraffins and C_7 cycloalkanes; recycling the overhead stream from the deisoheptanizer to the C_5 - C_6 isomerization zone; combining the bottom stream from the deisoheptanizer with the bottom stream from the deisohexanizer to form a combined stream; isomerizing the combined stream in a second C_7 isomerization zone at second isomerization conditions favoring the formation of cyclopentanes over cyclohexanes to form a second C_7 isomerization effluent; reforming the heavy stream from the naphtha splitter in a reforming zone under reforming conditions forming a reformate effluent; blending one or more of: the first stream from the deisohexanizer, the sidecut stream from the deisoheptanizer, the second C_7 isomerization effluent, or the reformate effluent to form a gasoline blend. An embodiment of the invention is one, any or all of prior embodiments in this paragraph up through the second embodiment in this paragraph wherein deisohexanizing the C_5 - C_6 isomerization effluent in the deisohexanizer into at least the first stream comprising multi-branched C_6 paraffins and the bottom stream comprising C_6 cycloalkanes and heavies comprises deisohexanizing the C_5 - C_6 isomerization effluent in the deisohexanizer into at least the first stream comprising multi-branched C_6 paraffins, and the bottom stream comprising C_6 cycloalkanes and heavies, and a lower sidecut stream comprising n- C_6 paraffins and single-branched C_6 and further comprising recycling the lower sidecut stream from the deisohexanizer to the C_5 - C_6 isomerization zone. An embodiment of the invention is one, any or all of prior embodiments in this paragraph up through the second embodiment in this paragraph further comprising; introducing an aromatic-containing stream comprising at least one aromatic to the second C_7 isomerization zone. An embodiment of the invention is one, any or all of prior embodiments in this paragraph up through the second embodiment in this paragraph wherein the first isomerization conditions include a temperature in a range of 40° C. to 235° C., or wherein the second isomerization conditions include a temperature in a range of 175° C. to 325° C., or both. An embodiment of the invention is one, any or all of prior embodiments in this paragraph up through the second embodiment in this paragraph further comprising blending at least one additional stream with the gasoline blend. An embodiment of the invention is one, any or all of prior embodiments in this paragraph up through the second embodiment in this paragraph further comprising hydropro-

cessing the naphtha feed before separating the naphtha feed. An embodiment of the invention is one, any or all of prior embodiments in this paragraph up through the second embodiment in this paragraph wherein the C_7 stream from the naphtha splitter further comprises at least one aromatic compound, and further comprising hydrogenating at least a portion of the aromatic compounds in the C_7 stream from the naphtha splitter before isomerizing C_7 stream from the naphtha splitter. An embodiment of the invention is one, any or all of prior embodiments in this paragraph up through the second embodiment in this paragraph further comprising at least one of separating the first C_7 isomerization effluent into an overhead stream comprising hydrogen and C_4 and lower boiling hydrocarbons and a second heavy stream comprising C_5 and heavier hydrocarbons before deisoheptanizing at least the portion of the first C_7 isomerization effluent, and wherein deisoheptanizing at least the portion of the first C_7 isomerization effluent comprises deisoheptanizing the second heavy stream; or separating the second C_7 isomerization effluent into a second overhead stream comprising hydrogen and C_4 and lower boiling hydrocarbons and a C_7 isomerized stream comprising C_5 and heavier hydrocarbons and wherein blending one or more of: the first stream from the deisohexanizer, the first stream from the deisoheptanizer, the second C_7 isomerization effluent, or the reformate effluent to form the gasoline blend comprises blending one or more of: the first stream from the deisohexanizer, the first stream from the deisoheptanizer, the C_7 isomerized stream, or the reformate effluent to form the gasoline blend; or separating the C_5 - C_6 isomerization effluent into at least a third overhead stream comprising C_4 and lower boiling hydrocarbons and a C_5 - C_6 isomerized stream comprising C_5 and heavier hydrocarbons, and wherein deisohexanizing at least the portion of the C_5 - C_6 isomerization effluent comprises deisohexanizing the C_5 - C_6 isomerized stream.

Without further elaboration, it is believed that using the preceding description that one skilled in the art can utilize the present invention to its fullest extent and easily ascertain the essential characteristics of this invention, without departing from the spirit and scope thereof, to make various changes and modifications of the invention and to adapt it to various usages and conditions. The preceding preferred specific embodiments are, therefore, to be construed as merely illustrative, and not limiting the remainder of the disclosure in any way whatsoever, and that it is intended to cover various modifications and equivalent arrangements included within the scope of the appended claims.

In the foregoing, all temperatures are set forth in degrees Celsius and, all parts and percentages are by weight, unless otherwise indicated.

What is claimed is:

- An integrated process for production of gasoline comprising:
separating a naphtha feed in a naphtha splitter into a light stream comprising C_6 and lighter boiling hydrocarbons, a C_7 stream comprising C_7 hydrocarbons, and a heavy stream comprising C_8 and heavier hydrocarbons;
isomerizing at least a portion of the light stream from the naphtha splitter in a C_5 - C_6 isomerization zone at isomerization conditions to form a C_5 - C_6 isomerization effluent;
deisohexanizing at least a portion of the C_5 - C_6 isomerization effluent in a deisohexanizer into at least a first stream comprising multi-branched C_6 paraffins and a bottom stream comprising C_6 cycloalkanes and heavies;

isomerizing the C₇ stream from the naphtha splitter in a first C₇ isomerization zone at first isomerization conditions favoring the formation of multi-branched C₇ paraffins and cyclohexanes to form a first C₇ isomerization effluent;

deisoheptanizing at least a portion of the first C₇ isomerization effluent in a deisoheptanizer into at least a first stream comprising multi-branched C₇ paraffins, and a bottom stream comprising n-C₇ paraffins and C₇ cycloalkanes;

combining the bottom stream from the deisoheptanizer with the bottom stream from the deisoheptanizer to form a combined stream;

isomerizing the combined stream in a second C₇ isomerization zone at second isomerization conditions favoring the formation of cyclopentanes over cyclohexanes to form a second C₇ isomerization effluent;

reforming the heavy stream from the naphtha splitter in a reforming zone under reforming conditions forming a reformate effluent;

blending one or more of: the first stream from the deisoheptanizer, the first stream from the deisoheptanizer, the second C₇ isomerization effluent, or the reformate effluent to form a gasoline blend.

2. The process of claim 1 wherein deisoheptanizing at least the portion of the first C₇ isomerization effluent in the deisoheptanizer into at least the first stream comprising multi-branched C₇ paraffins and the bottom stream comprising n-C₇ paraffins and C₇ cycloalkanes comprises deisoheptanizing at least the portion of the first C₇ isomerization effluent in the deisoheptanizer into at least an overhead stream comprising C₆ paraffins, the first stream comprising multi-branched C₇ paraffins, and the bottom stream comprising n-C₇ paraffins and C₇ cycloalkanes; and further comprising:

recycling the overhead stream from the deisoheptanizer to the C₅-C₆ isomerization zone.

3. The process of claim 1 wherein deisohexanizing the C₅-C₆ isomerization effluent in the deisohexanizer into at least the first stream comprising multi-branched C₆ paraffins and the bottom stream comprising C₆ cycloalkanes and heavies comprises deisohexanizing the C₅-C₆ isomerization effluent in the deisohexanizer into at least the first stream comprising multi-branched C₆ paraffins, and the bottom stream comprising C₆ cycloalkanes and heavies, and a lower sidecut stream comprising n-C₆ paraffins and single-branched C₆ paraffins and further comprising:

recycling the lower sidecut stream from the deisohexanizer to the C₅-C₆ isomerization zone.

4. The process of claim 1 further comprising, introducing an aromatic-containing stream comprising at least one aromatic to the second C₇ isomerization zone.

5. The process of claim 1 wherein the first isomerization conditions include a temperature in a range of 40° C. to 235° C., or wherein the second isomerization conditions include a temperature in a range of 175° C. to 325° C., or both.

6. The process of claim 1 further comprising, blending at least one additional stream with the gasoline blend.

7. The process of claim 1 further comprising, hydroprocessing the naphtha feed before separating the naphtha feed.

8. The process of claim 1 wherein the C₇ stream from the naphtha splitter further comprises at least one aromatic compound, and further comprising:

hydrogenating at least a portion of the aromatic compounds in the C₇ stream from the naphtha splitter before isomerizing the C₇ stream from the naphtha splitter.

5 9. The process of claim 1 further comprising: separating the first C₇ isomerization effluent into an overhead stream comprising hydrogen and C₄ and lower boiling hydrocarbons and a second heavy stream comprising C₅ and heavier hydrocarbons before deisoheptanizing at least the portion of the first C₇ isomerization effluent, and wherein deisoheptanizing at least the portion of the first C₇ isomerization effluent comprises deisoheptanizing the second heavy stream.

10. The process of claim 1 further comprising: separating the second C₇ isomerization effluent into a second overhead stream comprising hydrogen and C₄ and lower boiling hydrocarbons and a C₇ isomerized stream comprising C₅ and heavier hydrocarbons and wherein blending one or more of: the first stream from the deisohexanizer, the first stream from the deisoheptanizer, the second C₇ isomerization effluent, or the reformate effluent to form the gasoline blend comprises blending one or more of: the first stream from the deisohexanizer, the first stream from the deisoheptanizer, the C₇ isomerized stream, or the reformate effluent to form the gasoline blend.

11. The process of claim 1 further comprising: separating the C₅-C₆ isomerization effluent into at least a third overhead stream comprising C₄ and lower boiling hydrocarbons and a C₅-C₆ isomerized stream comprising C₅ and heavier hydrocarbons, and wherein deisohexanizing at least the portion of the C₅-C₆ isomerization effluent comprises deisohexanizing the C₅-C₆ isomerized stream.

12. The process of claim 1, further comprising at least one of:

sensing at least one parameter of the process and generating a signal or data from the sensing; generating and transmitting a signal; or generating and transmitting data.

13. The process of claim 12 wherein the first isomerization conditions include a temperature in a range of 40° C. to 235° C., or wherein the second isomerization conditions include a temperature in a range of 175° C. to 325° C., or both.

14. An integrated process for production of gasoline comprising:

separating a naphtha feed in a naphtha splitter into a light stream comprising C₆ and lighter boiling hydrocarbons, a C₇ stream comprising C₇ hydrocarbons, and a heavy stream comprising C₈ and heavier hydrocarbons; isomerizing at least a portion of the light stream from the naphtha splitter in a C₅-C₆ isomerization zone at isomerization conditions to form a C₅-C₆ isomerization effluent;

deisohexanizing at least a portion of the C₅-C₆ isomerization effluent in a deisohexanizer into at least a first stream comprising multi-branched C₆ paraffins and a bottom stream comprising C₆ cycloalkanes and heavies;

isomerizing the C₇ stream from the naphtha splitter in a first C₇ isomerization zone at first isomerization conditions favoring the formation of multi-branched C₇ paraffins and cyclohexanes to form a first C₇ isomerization effluent;

deisoheptanizing at least a portion of the first C₇ isomerization effluent in a deisoheptanizer into at least an

25

- overhead stream comprising C₆ paraffins, a sidecut stream comprising multi-branched C₇ paraffins, and a bottom stream comprising n-C₇ paraffins and C₇ cycloalkanes;
 recycling the overhead stream from the deisoheptanizer to the C₅-C₆ isomerization zone;
 combining the bottom stream from the deisoheptanizer with the bottom stream from the deisoheptanizer to form a combined stream;
 isomerizing the combined stream in a second C₇ isomerization zone at second isomerization conditions favoring the formation of cyclopentanes over cyclohexanes to form a second C₇ isomerization effluent;
 reforming the heavy stream from the naphtha splitter in a reforming zone under reforming conditions forming a reformate effluent;
 blending one or more of: the first stream from the deisoheptanizer, the sidecut stream from the deisoheptanizer, the second C₇ isomerization effluent, or the reformate effluent to form a gasoline blend.
- 15
16. The process of claim 14 wherein deisoheptanizing the C₅-C₆ isomerization effluent in the deisoheptanizer into at least the first stream comprising multi-branched C₆ paraffins and the bottom stream comprising C₆ cycloalkanes and heavies comprises deisoheptanizing the C₅-C₆ isomerization effluent in the deisoheptanizer into at least the first stream comprising multi-branched C₆ paraffins, and the bottom stream comprising C₆ cycloalkanes and heavies, and a lower sidecut stream comprising n-C₆ paraffins and single-branched C₆ and further comprising:
 recycling the lower sidecut stream from the deisoheptanizer to the C₅-C₆ isomerization zone.
- 20
17. The process of claim 14 further comprising:
 introducing an aromatic-containing stream comprising at least one aromatic to the second C₇ isomerization zone.
- 25
18. The process of claim 14 further comprising:
 introducing an aromatic-containing stream comprising at least one aromatic to the second C₇ isomerization zone.
- 30
19. The process of claim 14 wherein the C₇ stream from the naphtha splitter further comprises at least one aromatic compound, and further comprising:
 introducing an aromatic-containing stream comprising at least one aromatic to the second C₇ isomerization zone.
- 35
20. The process of claim 14 further comprising:
 introducing an aromatic-containing stream comprising at least one aromatic to the second C₇ isomerization zone.

26

18. The process of claim 14 further comprising:
 hydroprocessing the naphtha feed before separating the naphtha feed.
19. The process of claim 14 wherein the C₇ stream from the naphtha splitter further comprises at least one aromatic compound, and further comprising:
 introducing an aromatic-containing stream comprising at least one aromatic to the second C₇ isomerization zone.
20. The process of claim 14 further comprising at least one of:
 separating the first C₇ isomerization effluent into an overhead stream comprising hydrogen and C₄ and lower boiling hydrocarbons and a second heavy stream comprising C₅ and heavier hydrocarbons before deisoheptanizing at least the portion of the first C₇ isomerization effluent, and wherein deisoheptanizing at least the portion of the first C₇ isomerization effluent comprises deisoheptanizing the second heavy stream; or
 separating the second C₇ isomerization effluent into a second overhead stream comprising hydrogen and C₄ and lower boiling hydrocarbons and a C₇ isomerized stream comprising C₅ and heavier hydrocarbons and wherein blending one or more of: the first stream from the deisoheptanizer, the sidecut stream from the deisoheptanizer, the second C₇ isomerization effluent, or the reformate effluent to form the gasoline blend comprises blending one or more of: the first stream from the deisoheptanizer, the sidecut stream from the deisoheptanizer, the C₇ isomerized stream, or the reformate effluent to form the gasoline blend; or
 separating the C₅-C₆ isomerization effluent into at least a third overhead stream comprising C₄ and lower boiling hydrocarbons and a C₅-C₆ isomerized stream comprising C₅ and heavier hydrocarbons, and wherein deisoheptanizing at least the portion of the C₅-C₆ isomerization effluent comprises deisoheptanizing the C₅-C₆ isomerized stream.
